CLAIM

The ornamental design for a tray for media disc, as shown and described.

DESCRIPTION

FIG. 1 is a perspective view of a tray for holding media disc showing our new design;

FIG. 2 is a perspective view of a second embodiment of the design shown in FIG. 1;

FIG. 3 is a top plan view of the design of FIG. 1;

FIG. 4 is a top plan view of the design of FIG. 2;

FIG. 5 is an end view, both ends appearing the same, of the designs of both FIG. 1 and FIG. 2;

FIG. 6 is a rear plan view, being the reverse of the top, of the designs of both FIG. 1 and FIG. 2;

FIG. 7 is a side elevation view, both sides appearing the same, of the designs of both FIG. 1 and FIG. 2; and,

FIG. 8 is a perspective view of the design of FIG. 2.

The broken line showing is included for the purpose of illustrating environment and forms no part of the claimed design.
